UNITED STATES PATENT OFFICE.

JOHN CHANCEY PARKER, OF BROCKPORT, NEW YORK, ASSIGNOR OF
ONE-HALF TO CHARLES ALBERT PARKER, OF POUGHKEEPSIE,
NEW YORK.

BARREL.

No. 828,899.

Specification of Letters Patent.

Patented Aug. 21, 1906.

Application filed November 8, 1905. Serial No. 286,394.

To all whom it may concern:

Be it known that I, JOHN CHANCEY PARKER, a citizen of the United States, residing at Brockport, in the county of Monroe and 5 State of New York, have invented a new and useful Improvement in Knockdown Barrels, of which the following is a specification.

My invention relates to an improvement in barrels, and particularly to the class of sectional or "knockdown" barrels; and the object thereof is to provide a strong, durable, and inexpensive construction that may be readily assembled or set up when desired for use and as readily disassembled when its 15 contents have been removed, so that it may be packed into a small bundle to occupy less space and also to facilitate transportation should it be desired to reship the barrel to the original merchant.

20 A further object of the invention is to provide means for securely locking the sections together and also means for locking the heads in position, the latter means being capable of independent operation, so that either 25 head of the barrel may be removed without disturbing the other fasteners.

Still a further object is to provide a construction in which the meeting edges of the sections will be practically smooth upon the 30 inside and outside of the barrel, avoiding all obstructions that would endanger or destroy the contents of the barrel while in the course of transportation, especially in the case of fruits, vegetables, and the like.

35 With these briefly-stated objects in view the invention also comprises certain details of construction and peculiar combination and arrangement of parts, as will be fully described in the following specification and 40 pointed out in the claims, reference being had to the drawings, in which—

Figure 1 is a perspective view of a barrel constructed in accordance with my invention. Fig. 2 is a vertical longitudinal section of the 45 same. Fig. 3 is a detail sectional view drawn on the line 3 3 of Fig. 2. Figs. 4 and 5 are detail perspective views of the sections forming the body part of the barrel. Figs. 6 and 7 are detail views of the heads. Figs. 8 and 50 9 are detail views of portions of the bands employed for contracting the ends of the barrel to hold the heads in position, the levers to which the ends of the bands are connected being shown in an unlocked position. Fig.

10 is a detail view showing a portion of one of 55 the locking-bands, illustrating the lever in the position it occupies when the band is extended. Fig. 11 is a similar view illustrating the position of the lever when the band is contracted, and Fig. 12 is a detail 60 view illustrating a slightly-modified construction for uniting the ends of the bands in lieu of the lever.

In carrying out my invention I construct the body of the barrel of two semicylindrical 65 sections A and B, which may be made with a bilge to assimilate ordinary barrels or perfectly straight throughout their length, according to the purpose for which the barrel is to be used.

70 The longitudinal edges of each section are provided with tongues C, which are produced by slitting the edges, as at C'. Each tongue is bent slightly at its base or the point adjacent the inner ends of the slits in alternate 75 directions to provide seats or recesses in which the interlocking tongues of the opposite sections may rest. This arrangement avoids all projections upon either side of the meeting edges of the sections and also increases security and prevents any longitudinal movement of either section should the barrel be handled carelessly during transportation and allowed to drop on one edge, as is often the case, especially in removing the barrels from wagons or cars.

80 At or near the upper and lower edge each section is bent outwardly and inwardly to provide two grooves D and E, which are continuous when the sections are put together. 90 The inner groove D at each end provides a croze for the heads F, which may be perfectly flat, concavo-convexed, or corrugated. The grooves E, which are upon the outside of the sections and adjacent the ends, are adapted 95 for the reception of locking-bands or split rings G G, whose ends are connected to locking-levers H, as shown in the main figures of the drawings, or to disks H', one of which is shown in Fig. 12 of the drawings; but in 100 either case after the bands or rings have been adjusted the levers or disks are securely locked in position by pieces of wire I, which are passed around the ends of the levers, under the bands, and through apertures in one 105 of the sections, the ends of the wires being twisted together or locked by means of lead seals. From the drawings it will be seen the

bands or rings are so connected to the levers that when the latter are thrown in the direction illustrated by the arrow in Fig. 10 to the position shown in Fig. 11 the bands or rings will be thrown together or contracted and caused to tightly contract the ends of the barrel. The locking arrangement avoids accidental movement of the levers, and consequently securely locks them and the bands in position.

In order to hold the sections securely together, especially when the barrels are used for transporting sugar or other heavy substances, I employ hoops or straps J, which are held in position between spurs K, projecting from each section of the barrel, said spurs being produced by punching the sections outwardly from the inside of the barrel and are preferably V shape, with their flat edges in horizontal alinement and against which the rings or bands engage. Of course it is understood that the spurs are not projected far enough to split the metal and cause an opening, but are only bent slightly to provide an obstruction to prevent the band slipping.

From the foregoing it will be seen that I provide an exceedingly cheap, simple, and highly-efficient device of the kind described, and it will be readily understood that in assembling the barrels the sections A and B are first put together and the bands secured in place, after which one head is arranged in position and locked by means of one of the bands G. The barrel is then filled, when the other head is inserted and locked in position by the band, and the barrel is then ready for shipment. It will of course be understood that when it is desired to gain access to the barrel one of the wires I is clipped and the lever is reversed, which releases or loosens the locking-band, and likewise the end of the barrel, when the head may be readily removed. It will also be understood that the same head as originally used may be again employed for temporarily resealing or "heading" the barrel after it has been first opened.

While I have shown the sections of the barrel solid and made for use in transporting sugar, flour, and like articles, it will be understood that the sides and heads may be perforated when used for transporting fruit, and the sides may also be corrugated should it be desired to do so.

Having thus fully described my invention, what I claim as new, and desire to secure by Letters Patent, is—

1. A barrel of the kind described, comprising a body formed of two sections, each having grooves at their upper and lower edges, one of which, at each end, providing a croze for the reception of the heads of the barrel, unbroken rows of tongues formed upon the longitudinal edges of each section, the tongues of one section engaging the tongues

of the opposite section in the same horizontal plane, heads held within the croze at each end of the barrel, and locking bands or rings engaging the sections, and means for locking the bands or rings in position.

2. A barrel of the kind described, comprising a body formed of semicylindrical sections, each having intermeshing tongues upon their longitudinal edges, the alternate tongues of each section being bent in opposite directions for the purpose specified, the said sections having grooves adjacent their upper and lower ends, one groove at each end providing a croze adapted for the reception of heads, split rings or bands adapted to fit in the grooves adjacent each groove forming the croze, levers to which the ends of the bands or rings are connected, and means for locking the levers against accidental displacement.

3. A barrel of the kind described, comprising a body portion formed of sections, each section having grooves at their upper and lower edges, one of which at each end providing a croze, intermeshing tongues formed upon the longitudinal edges of each section, spurs projecting from each section in horizontal alinement, hoops or straps for holding the sections together, said hoops or straps being held in position by the said spurs, and split rings or bands for contracting the ends of the barrel, and means for holding the rings or bands in position.

4. A barrel of the kind described, comprising a body portion formed of two sections, each having grooves at its upper and lower edges which are continuous when the sections are arranged together, tongues formed upon the longitudinal edges of each section, two rows of spurs arranged near the upper and lower ends of each section, said spurs being arranged in horizontal alinement, hoops or straps for holding the sections together, said straps being held between and engaged by each row of spurs, split rings or bands adapted to fit in the grooves at each end of the barrel, levers to which the ends of the rings or bands are connected and by which the bands are contracted within the grooves, and wires adapted for fastening the levers in position after the bands have been contracted, all substantially as specified.

5. A barrel of the kind described, comprising a sectional body portion, each section having two grooves at each end, one of the said grooves forming a croze, tongues provided at the longitudinal edges of each section, said tongues being alternately offset to provide seats for the tongues of the opposite section, two horizontal rows of spurs projecting exteriorly from each section, hoops or straps for holding the sections together, said hoops or straps being held in position by the said spurs, split rings or bands for contracting the ends of the barrel, means for contracting the ends of the rings or bands, said

means serving to contract the ends of the barrel.

6. A barrel of the kind described, comprising a sectional body portion, each section having grooves adjacent its ends, one of which at each end providing a croze, tongues formed upon the longitudinal edges of each section of the body, hoops or straps encircling the barrel and adapted for holding the sections together, spurs projecting outwardly from each section and engaging the said bands, a head held within the croze at each end of the barrel, a split ring or band arranged within the grooves adjacent each croze and adapted for contracting the ends of the barrel to hold the heads in position, levers to which the ends of the bands are con-

nected and by which the said bands are contracted, and means for locking the levers in position, all substantially as specified. 20

7. A barrel of the kind described comprising a body formed of sections, each section having its longitudinal edges slotted to produce unbroken rows of tongues, each tongue being bent in opposite directions and adapted for engagement with the tongues upon the opposite section that are arranged in the same horizontal plane and means for holding the sections together. 25
